UNITED STATES PATENT OFFICE.

WILLIAM A. NEELY, OF LYNN, MASSACHUSETTS, ASSIGNOR TO THE WHEELER & WILSON MANUFACTURING COMPANY, OF BRIDGEPORT, CONNECTICUT.

TRIMMING MECHANISM FOR SEWING-MACHINES.

SPECIFICATION forming part of Letters Patent No. 628,227, dated July 4, 1899.

Application filed August 15, 1898. Serial No. 688,647. (No model.)

To all whom it may concern:

Be it known that I, WILLIAM A. NEELY, of Lynn, county of Essex, State of Massachusetts, have invented an Improvement in Trimming Mechanism for Sewing-Machines, of which the following description, in connection with the accompanying drawings, is a specification, like letters and figures on the drawings representing like parts.

- 10 In some classes of work, notably boot and shoe work, it frequently happens that a folded edge is to be stitched upon material underlying it and the free edge of the underlying material is to be cut off substantially in line with the folded edge. The apparatus to be herein described has been especially devised for doing this class of trimming, and owing to the peculiar construction and location of the parts it is possible to trim the free edge 20 at a point more or less within the line of the folded edge, this being especially desirable in connection with shoe-tops.

In this invention the cutter-carrying bar is arranged to slide in guideways in an angular direction transverse to the line of direction of the seam being stitched or the feed, such location enabling the blade to pass under the folded edge referred to. To coöperate with this folded edge, I have arranged an edge-gage which contacts with the folded edge between the cutter-blade and the operator, the cutting edge of the blade reciprocating in a plane outside of the acting face of the said gage, so that under no circumstances can the cutting edge of the blade meet and mar the folded edge of the material, which is often finished leather. The edge-gage is spring-pressed, so that it may bear upon the surface which is to be removed by trimming 40 and may yield to any variation in thickness thereof, and this edge-gage is so pivoted that no amount of pressure of the folded edge against it will tend to lift or displace the edge-gage. The bar carrying the cutter-blade 45 has connected to it an operating-link which is attached to an elbow-lever driven by a rock-shaft which may be slid longitudinally in a suitable bearing; so that a roller or other stud carried thereby and entering a hole in said 50 elbow-lever may be moved to enter a groove

in a cam on the main rotating shaft of the machine to thereby reciprocate the said bar, or by a movement of said rock-shaft longitudinally in the opposite direction, which may be done at any moment, the said roller 55 or other stud may be removed from the influence of said cam, and the cutter-bar and its cutter, as well as the edge-gage, may be lifted entirely from the work, leaving the sewing parts to operate without any interference with either of the same. This provision of withdrawing the knife and gage from operative position temporarily is essential in many classes of work being done.

I believe myself to be the first to employ a 65 cutter-bar having a blade adapted to be reciprocated in an inclined plane transverse to the direction of feed, and also I believe myself to be the first to so combine with such a cutter-bar and blade an edge-gage which may 70 be put into its inoperative position when the cutter-bar is thrown out of action, and hence this invention is not limited to the exact devices herein shown and described, but I may employ instead any other usual or equivalent devices having the same method of operation.

Figure 1, in side elevation, represents a sufficient portion of a well-known sewing-machine with my improvements added to enable 80 my invention to be understood, the presser-foot being shown in its elevated position, but with the blade of the cutter and its edge-gage in their operative positions. Fig. 2 is a detail taken from the rear side of Fig. 1, chiefly 85 to show the cutter-blade, its carrying-bar and the edge-gage, and means for operating said bar, said figure also showing part of the presser-foot and with material thereunder in position to be sewed and trimmed. Fig. 3 is 90 a sectional detail to the left of the line α , Fig. 1. Fig. 4 is a sectional detail showing the elbow-lever and the means for operating it. Fig. 5 shows the rock-shaft, its arm having a stud entering said lever, and a second lever, 95 which is withdrawn from the cam. Fig. 6 shows the lower end of the bar with its attached blade or cutter and a folded edge lying on, it may be, a shoe-lining which is to be trimmed away simultaneously with the 100

stitching operation. Fig. 7 is a detail of the blade. Fig. 8 is a partial plan view of the parts shown in Fig. 6, it also showing the edge-gage in position against an edge of the material, the figure showing the line of stitches and the line in which the underlying material or lining is cut. Fig. 9 is a detail showing part of Fig. 2, but with the blade and gage elevated in their inoperative position above the work-plate. Fig. 10 is a plan view of the throat-plate, and Fig. 11 a sectional detail thereof to show the blade-passage.

The bed-plate A, the overhanging arm A', the needle-bar A², having an eye-pointed needle a, the presser-foot A³, shown as a roller, it being carried by a vertically-movable presser-bar, the take-up A⁴, the tension A⁵, the main shaft A⁶ in the overhanging arm and deriving its motion from the pulley A⁷, fast on the said shaft, and the links A⁸, connected with said shaft and extended downwardly to the double cranks of the lower shaft for actuating the stitch-forming mechanism located below the bed-plate and complementary to the needle-bar and needle, are and may be all substantially as represented in the well-known Wheeler & Wilson sewing-machine on the market, so that said parts need not be herein further described.

30 The upper side of the overhanging arm A' supports a stand B, which receives a hollow rock-shaft B', (see Fig. 5,) having fixed to it at one end an elbow-lever B², a depending arm of said lever having a hole B³, (see Fig. 5,) while the other or longer arm of said lever receives a stud-screw B⁴, which is surrounded by the upper end of a link B⁵, the lower end of which in turn surrounds a pin or projection B⁶, extended from a collar B⁷, fast on the bar B⁸, to which is attached the blade or cutter B⁹.

45 The hollow rock-shaft B' receives through it a shaft C, having at one end an arm or disk C', provided, as herein shown, with a stop-pin C², it serving to limit the sliding motion of the said rod C in the hollow rock-shaft B'.

50 The rod C is reduced in diameter near one end and is thereby left with a shoulder C⁴, against which bears one end of a spring C⁵, so that said spring normally acts to move the said rod in the direction of the arrow thereon in Fig. 5.

55 The outer end of the rod C has fixed upon it an arm C⁶, having a stud C⁷, which enters the hole B³ in the short arm of the elbow-lever B², and said arm also has at its lower end a roller or other stud C⁸, which may enter the cam-groove in the hub C⁹, attached to the main shaft A⁶, said stud when in said groove causing the arm C⁶ to be vibrated and through the stud C⁷ in the hole of said elbow-lever vibrating the elbow-lever and reciprocating the blade-carrying bar B⁸ to effect the trimming of the work; but whenever it is desired to put the said blade and bar in their inoperative position the attendant has merely to

push the rod C in the rock-shaft in a direction opposite the arrow thereon, such movement removing the roller or other stud C⁸ out from the groove of the cam, and immediately thereafter a spiral or other spring C¹⁰ acts to move the said arm C⁶ and elbow-lever to the right into the dotted-line position, Fig. 2, leaving the elbow-lever and the bar and blade 75 at rest. To again start the trimming mechanism into operation, the operator merely presses upon the projection or handpiece D, extended from the disk or arm C', which turns the said rock-shaft in opposition to the spring 80 C¹⁰, bringing the roller or other stud C⁸ in line with the cam-groove before actuating it, when the spring C⁵ immediately acts and causes said roller or other stud to enter said cam-groove.

85 As herein shown, the under side of the arm A' has suitably bolted to it a frame D², it being located at one side of the same and extended diagonally toward the line of seam and feed, said frame being provided with 90 suitable bearings D³ and D⁴, in which is free to slide the bar B⁸, before described.

95 The bar B⁸ has a second collar D⁵, provided with an extended pin D⁶, which enters a slot in the upper end of an elbow-lever D⁷, fulcrumed loosely on a screw-stud D⁸, said stud being passed through a slot d in said lever, a spring d', connected to the upper end of said lever and to the bearing D⁴, serving to keep the upper end of the slot in said lever 100 upon the upper side of the stud-screw.

105 The short arm 2 of the elbow-lever D⁷ receives the edge-gage 3, it being held in adjusted position therein by a set-screw 4, and the spring d' keeps the acting end of said edge-gage normally pressed in a yielding manner upon the surface of the material which is to be trimmed from underneath the folded part. In case, however, it is not desired that the end of the gage should bear 110 upon the material to be trimmed off then the set-screw 5 (see Fig. 1) may be turned so that its inner end acting against the elbow-lever D⁷ will limit the descent of the gage under the spring d'.

115 During the reciprocations of the rod B⁸ and the trimming of the material through the devices described the stud D⁶ slides up and down in the slot of the elbow-lever, but does not turn the said elbow-lever upon its fulcrum, the stud-screw D⁸. Whenever, however, it is desired to remove the blade of the cutter and the edge-gage from operative position--as, for instance, while some other part of the work is being stitched which it is not necessary to trim--the operator, as hereinbefore described, throws the lever B² out of operative position with relation to the cam C⁹, and in such position the said elbow-lever through the link B⁵ pulls the bar B⁸ upwardly 120 diagonally in its bearings D³ D⁴, and at the same time the stud D⁶ in a slot of the elbow-lever acts upon the end of said slot and raises the elbow-lever with its edge-gage, the slot d

in the lower end of said elbow-lever at such time sliding on the fulcrum D⁸.

The slot d is so shaped that the elbow-lever D⁷, carrying the edge-gage, may rise to enable the edge-gage to adapt itself to the thickness of the material under it without removing the edge-gage laterally away from the folded edge e of the material lying on the part e' on or above which the edge-gage rests or travels.

The slot d is so shaped that when the lever D⁷ is in its operative position and the acting part of the edge-gage bears against the folded edge of the material being stitched to the material e' to be trimmed no amount of pressure of the said folded edge against the edge-gage will move it laterally away from the line of seam. The curve in the lower end of the slot d as the lever D⁷ is fully elevated gives a quick lateral movement to the lever and to the edge-gage, so that the latter is removed entirely from the path of the needle-bar as the latter continues to operate the stitch. It will be noticed that the needle-bar reciprocates in a vertical plane and that the bar B⁸, carrying the blade B⁹, reciprocates in an inclined plane at one side the line of seam and in a plane transverse to the direction of the feed and the direction of the seam being sewed, so that said blade is free to work under the edge e, as represented in Fig. 6, and cut off the lining or other material e' to which the said edge is being stitched, leaving the said cut edge substantially inside of the line of the edge.

To enable the blade B⁹ to be reciprocated in its transverse position, it becomes necessary to change the slot in the throat-plate through which the blade reciprocates.

Figs. 10 and 11 show the throat-plate d¹⁰, having the needle-hole d', feed-passage d'', and slot in which moves the spring-controlled sliding block d³, said block closing one side of the slot in which the blade of the cutter acts. Herein I have beveled the acting edge of said block at that side toward the needle-hole and have also beveled the under side of the throat-plate next the acting end of said block, so that I have formed a diagonal or inclined passage in which the said blade may work.

The shank of the blade B⁹ has a slot e³, which is entered by suitable set-screws e⁴, threaded into an adjustable knife or blade support e⁵, said knife-support having at its upper end a block e⁶, slotted to receive the rather small shank of the set-screw e⁷, said set-screw attaching the block and support in an adjustable manner to the lower end of the bar B⁸. The inner side of the block e⁶ has a groove which embraces a little spline made on the bar B⁸ (see Fig. 3) to insure the right line of adjustment of the said block and support with relation to said bar. This adjustment is of especial importance in the trimming mechanism herein described for the reason that it enables the block and the blade to be moved

with relation to the bar in order that the pointed end e⁸ of the blade and its cutting edge just above it may correctly enter the slot 70 in the throat-plate and not bind therein in any adjustments of the throat-plate for closer or wider trimming, such adjustments being well understood.

The stud B⁶, extended from the collar B⁷, 75 fast on the bar B⁸, is extended through a forked guide f, herein shown as secured to the guide-frame D² by suitable set-screws f', said stud working in said guideway preventing any rocking motion to the bar in its reciprocation and insuring the proper position of the cutting edge of the blade. The guideways so formed receive through them a suitable clamping-screw f², the rotation of which enables any wear to be compensated for. The edge 85 e may be a folded edge.

Having fully described my invention, what I claim, and desire to secure by Letters Patent, is—

1. In a sewing-machine, the following instrumentalities, viz: stitch-forming mechanism, a work-support, feeding mechanism to move said material over said work-support, a reciprocating trimming-blade, means to support said blade in a diagonal position in a vertical plane at one side of and transverse to the line of feed and of stitching, and a throat-plate having its under side shaped to coöperate with said inclined blade and form a second member of the trimming mechanism, substantially as described. 90

2. In a trimming mechanism for sewing-machines, an edge-gage standing above the material to be removed by a trimming-blade, said edge-gage serving to guide the edge of 105 the material from under which projects the edge of other material to be trimmed, a reciprocating trimming-blade, means to support said blade in a diagonal position in a vertical plane transverse to the line of feed and of 110 stitching, combined with a throat-plate beveled at its under side to receive said inclined blade, to operate, substantially as described.

3. In a trimming mechanism for sewing-machines, a reciprocating trimming-blade, combined with an edge-gage, a lever carrying said edge-gage and presenting its acting end above the material to be trimmed, and means to automatically move said lever when the blade is put into its inoperative position to thereby 120 lift the said edge-gage and at the same time move it laterally away from the line of stitching, substantially as described. 115

4. In a trimming mechanism for sewing-machines, a reciprocating trimming-blade, means 125 to support said blade in a diagonal position in a vertical plane at one side of and transverse to the line of feed and of stitching, combined with a throat-plate beveled at its under side to receive said inclined blade, to operate 130 substantially as described.

5. In a trimming mechanism for sewing-machines, a bar having an attached blade, coöperating means against which said blade may

- act to trim the material, a guide for said bar to keep it in a diagonal position at one side the line of stitching and feed, means to reciprocate said bar in said guide transversely 5 to the line of stitching and of feed, and an edge-gage, a lever upon which it is mounted, and means between said bar and lever to cause said lever and gage to follow said bar into its inoperative position when it is desired to place 10 the cutter-bar and gage out of action, substantially as described.
6. In a trimming mechanism for sewing-machines, an edge-gage connected with a slotted lever, a fulcrum for said lever, and a spring 15 to keep said lever seated on said fulcrum, substantially as described.
7. In a trimming mechanism for sewing-machines, an edge-gage secured to an elbow-lever provided with a slot, a fulcrum for said 20 lever, a spring to keep said lever seated on said fulcrum, the junction of the gage with the lever being so located that lateral pressure upon the edge-gage may be resisted by said fulcrum, substantially as described.
- 25 8. In a trimming mechanism for sewing-machines, an edge-gage, an elbow-lever to carry it, said elbow-lever having a cam-slot at its lower end, a fulcrum for said elbow-lever, said fulcrum being extended through said cam-slot, means to sustain said fulcrum, and means coacting with said elbow-lever to adjust the same to regulate the position of the edge-gage with relation to the material underlying it and to be trimmed away, substantially as de- 30 scribed.
- 35 9. In a trimming mechanism for sewing-machines, an edge-gage, an elbow-lever having a cam-slot near its lower end, a fulcrum for said elbow-lever, a spring to retain said elbow- 40 lever seated on said fulcrum, said elbow-lever having at its upper end a slot, combined

with a reciprocating bar carrying a trimmer-bar, said bar having a stud entering the slot at the upper end of said elbow-lever, whereby when said bar is elevated into its inoperative 45 position, said stud, acting in said slot, will elevate the elbow-lever and its attached edge-gage causing the cam-slot at its lower end to travel on said fulcrum and move the edge-gage laterally at the same time it is elevated, 50 substantially as described.

10. In a trimming mechanism for sewing-machines, a bar, a guide to hold said bar in a diagonal plane at one side of the line of seam and direction of feed, a support for the blade, 55 said support being adjustably attached to the lower end of said bar, and a blade adjustably secured to said support, combined with a throat-plate, an edge-gage, and means to reciprocate said bar in a diagonal path trans- 60 verse to the direction of feed and of the seam being sewed by the stitch-forming mechanism, substantially as described.

11. In a sewing-machine, the combination with a vertically-reciprocating needle, of a 65 trimming-knife which is inclined relatively to the vertical plane and sidewise to the seam, or the direction of the feed of the work, a throat-plate coöperating with said knife and means for reciprocating the said knife in the 70 direction of its length; whereby the edge of the lower layer of two superposed layers of material being sewed together may be trimmed off within the edge of the upper layer.

In testimony whereof I have signed my 75 name to this specification in the presence of two subscribing witnesses.

WILLIAM A. NEELY.
